UNITED STATES PATENT OFFICE.

GEORGE W. BOWEN, OF AUBURN, NEW YORK.

GREASE-CUP.

1,054,668.

Specification of Letters Patent.

Patented Mar. 4, 1913.

Application filed July 27, 1911. Serial No. 640,751.

To all whom it may concern:

Be it known that I, GEORGE W. BOWEN, of Auburn, in the county of Cayuga and State of New York, have invented a new and useful Grease-Cup, of which the following is a specification.

This invention has for its object the production of a grease cup which is particularly simple in construction, economical in manufacture and highly efficient and durable in use; and it consists in the combinations and constructions hereinafter set forth and claimed.

In describing this invention reference is had to the accompanying drawing in which like characters designate corresponding parts in all the views.

Figure 1 is a vertical sectional view of one form of my grease cup, and Fig. 2 is a view similar to Fig. 1 of another form thereof.

This grease cup comprises, generally, a base, a closure for the base, a follower movable toward and from the bottom of the base, and means carried by the closure for operating the follower.

1 is the base which is in the form of a receptacle, said base being provided at its lower end with an axially extending nipple 2 by means of which the cup is connected to the part to be lubricated, the nipple having a passage 3 therethrough which communicates with the interior of the base 1.

4 is the head of the closure for the base, the closure being also in the form of a receptacle and having a barrel portion 5 projecting from the head 4 into the base 1 and normally terminating near the bottom 6 of the base. The closure is externally threaded and turns into internal threads of the base 1.

40 In order to prevent grease within the closure from following upwardly between the threads of the closure and the cap, the lower end of the closure engages, and embeds in a packing ring 7 of yielding material located at the bottom 6 of the base 1. The head 4 overlaps the upper edge of the open end of the base 1, and opposing surfaces of the head and base are formed with a recess and a socket designed to come into alignment when the closure approaches the limit of its movement into the base 1, and a spring-pressed locking part is located in the socket and projects therefrom in position to enter the recess.

55 In the illustrated embodiment of my invention the base 1 is formed with a recess

or notch 8 in its upper edge said notch decreasing in depth toward opposite sides of the notch extending through the periphery of said edge and the head is formed with a 60 socket or perforation 9 extending through upper and lower surfaces thereof, in which socket the spring-pressed locking part as a ball 10 for entering the notch 8 is arranged, said locking part having a rounded lower 65 portion projecting from the contiguous part of the head for entering the notch when the perforation 9 is aligned therewith, and for coacting with opposite diverging sides of the notch during the turning movement of 70 the closure and thus the locking part moves downwardly into operative position, or rises therefrom by the mere turning movement of the closure.

The spring means acting on the ball 10 75 preferably consists of a disk 11 of resilient material mounted on the head and arranged coaxially therewith and with its margin extending across the upper end of the perforation 9, said disk being held at its 80 center and having its margin free. The disk 11 is usually arranged in a recess 12 located in the upper side of the head 4 and formed by a marginal annular flange 13 extending upwardly from the head 4. Such 85 recess 12 is closed by a disk 14 of sheet metal resting against a seating surface 15 near the upper edge of the flange 13, the disk 14 being held in position by spinning the upper edge of the flange 13 over on the upper face 90 of the margin of the disk 14 into a position opposed to the seating surface 15, as clearly seen at 16, Fig. 1.

17 is a follower movable between the head 4 and the bottom 6 of the base, said follower 95 engaging the inner circumferential face of the barrel portion 5 of the closure. The means for operating the follower comprises a threaded stem 18 extending axially through a threaded central opening of the 100 follower 17 and upwardly through the head 4 and disks 11 and 14, the stem being held from endwise movement by an annular thrust bearing 19 engaging the bottom of a socket formed in the inner face of the head 4, and 105 by a thrust bearing surface 20 on the outer end of the stem 18, said surface 20 abutting against a washer 21 encircling the stem 18 and resting on the disk 14. The disk 14 is held from yielding movement toward the 110 disk 11 by a washer 22 similar to the washer 21, the washer 22 encircling the stem 18

and being interposed between said disks 11 and 14. The bearing surface 20 is provided on the handle 23 for turning the stem 18, and such bearings 19 and 20 in addition to holding the stem 18 from endwise movement also hold the disk 11 at its center so that its margin will act as a spring against the ball 10. The follower 17 is held from turning movement with the stem 18 by suitable collapsible means interposed between opposing surfaces of the head 4 and the follower, said means being here shown as in the form of a conical spiral spring 24 fixed at one end to the head 4 and at its other end to the follower 17.

In order to prevent crushing of the spring 24 or other collapsible means, one of the parts provided with the opposing surfaces between which said spring 24 is interposed, is formed with an annular shoulder projecting toward the other of said opposing surfaces, the annular shoulder being concentric with the spring and of greater diameter than the largest diameter thereof in order that when the follower 17 is moved near the head 4, the spring 24 will be coiled within the annular shoulder. As shown in Fig. 1 the annular shoulder 25 is provided on the head 4 but as shown in Fig. 2 such shoulder is provided on the follower as indicated at 26.

In operation, the closure is unscrewed from the base 1 and the handle 23 operated to move the follower 17 upwardly to a position near the head 4 of the closure. The closure is then filled with grease and screwed into the base 1 until locked from turning movement by the ball 10. As the lubricant is used the follower is forced toward the bottom of the base by turning the handle 23.

What I claim is:

1. A grease cup comprising a base, a closure for the base connected thereto by screw threads, the base being formed with a notch, and the closure having a head formed with a socket, the movement of the closure serving to bring the socket into alignment with the notch, a locking part located in the socket and having a portion thereof projecting beneath the contiguous part of the head for entering the notch, said locking part being movable above said contiguous part and a resilient flattened member mounted on the upper surface of said contiguous part of the head and engaging the locking part for yieldingly forcing the same into locking position, substantially as and for the purpose set forth.

2. A grease cup comprising a base, a closure for the base connected thereto by screw threads, the upper edge of the base being formed with a notch, and the closure having a head overlapping said upper edge and formed with a socket, the movement of the closure serving to bring the socket into

alignment with the notch, a locking part located in the socket and having its lower portion projecting from the contiguous part of the head for entering the notch, and a resilient disk carried by the head and having its margin coacting with the locking part for forcing the same into its locking position, substantially as and for the purpose described.

3. A grease cup comprising a base, a closure for the base connected thereto by screw threads, the closure having a head overlapping the upper edge of the base, and the base being formed with a notch in its upper edge, and the head being formed with a perforation therethrough arranged to be brought into alignment with the notch when the closure approaches the limit of its movement toward the base, a resilient flattened member mounted on the head and extending across the upper end of the perforation, and a locking part located in the perforation for entering the notch, the locking part being engaged by said resilient member, substantially as and for the purpose set forth.

4. A grease cup comprising a base, a closure for the base, the closure having a head provided with a perforation extending through upper and lower surfaces thereof, at one side of the axis of the head, a locking part located in the perforation and having a portion thereof normally projecting beyond one of said surfaces and coacting with the base, and a resilient disk for yieldingly forcing the locking part into its normal position, said disk being arranged coaxially with the head and mounted on the other of said surfaces, substantially as and for the purpose described.

5. A grease cup comprising a base, a closure for the base connected thereto by screw threads, the base being formed with a notch, and the closure having a head formed with a perforation extending through upper and lower surfaces of the head, the movement of the closure serving to bring the perforation into alignment with the notch, a locking part located in the perforation and having a portion thereof projecting from the contiguous part of the head for entering the notch, and a resilient disk arranged coaxially with the head and mounted on the upper surface through which the perforation extends and coacting with the locking part for yieldingly forcing the same into its locking position, substantially as and for the purpose set forth.

6. A grease cup comprising a base, a closure for the base connected thereto by screw threads, the closure having a head overlapping the edge of the base and the base being formed with a notch in said edge, and the head being formed with a perforation therethrough arranged to be brought into alignment with the notch when the closure ap-

proaches the limit of its movement toward the base, a resilient disk mounted on the head and arranged with its margin extending across the upper end of said perforation, the disk being held at its center and having its margin free, and a locking part located in the perforation for entering said notch, the locking part being pressed out of the perforation by the disk, substantially as and for the purpose described.

7. A grease cup comprising a base, a closure for the base, the closure having a head provided with an upwardly extending annular flange on its upper surface and with a perforation extending through a lower surface of the head and the portion of said upper surface encircled by the flange, a locking part located in the perforation and having a portion thereof normally projecting beyond said lower surface and coacting with the base, and a resilient disk for yieldingly forcing the locking part into its normal position, said disk being arranged coaxially with the head and mounted within the flange on the portion of said upper surface encircled by the flange, substantially as and for the purpose specified.

8. A grease cup comprising a base, a closure for the base connected thereto by screw threads, the base being formed with a notch, and the closure having a head formed with an upwardly extending annular flange, and with a perforation extending through the lower surface of the head, and an upper surface of the head encircled by the flange, the movement of the closure serving to bring the perforation into alignment with the notch, a locking part located in the perforation and having a portion thereof projecting from the contiguous part of the head for entering the notch, and a resilient member arranged within the flange and coacting with the locking part for yieldingly forcing the same into its locking position, substantially as and for the purpose specified.

9. A grease cup comprising a base, a closure for the base connected thereto by screw threads, the closure having a head overlapping the upper edge of the base, the base being formed with a notch in its edge opposed to the head, and the head being formed with a perforation arranged to come into alignment with the notch as the closure approaches the limit of its movement toward the base, the head being formed with an upwardly extending annular flange, a spring disk mounted on the head and arranged within the flange and having its margin extending across the upper end of said perforation, the disk being held at its center and having its margin free, and a locking part located in the perforation for entering the notch, the locking part being pressed out of the perforation by the disk, substantially as and for the purpose specified.

10. A grease cup comprising a base, a closure for the base connected thereto by screw threads, the base being formed with a notch, and the closure having a head formed with an upwardly extending annular flange, and with a perforation extending through the lower surface of the head, and an upper surface of the head encircled by the flange, the movement of the closure serving to bring the perforation into alignment with the notch, a disk having its margin engaged with the upwardly extending annular flange, a locking part located in the perforation beneath the disk and having a portion projecting from the contiguous part of the head for entering the notch, and a spring member arranged beneath the disk and within the annular flange and coacting with the locking part for yieldingly forcing the same into its locking position, substantially as and for the purpose described.

11. A grease cup comprising a base, a closure for the base connected thereto by screw threads, the closure having a head overlapping the edge of the base, the base being formed with a notch in its edge opposed to the head and the head being formed with a perforation arranged to come into alignment with the notch as the closure approaches the limit of its movement toward the base, the head being also formed with an upwardly extending marginal annular flange, the flange being formed with a seat, a disk having its margin resting on said seat, and the edge of the flange being spun inwardly on the upper face of such margin into a position opposed to said seat, and a spring pressed locking member mounted in the perforation beneath the disk, substantially as and for the purpose specified.

12. A grease cup comprising a base, a closure for the base connected thereto by screw threads, the base being formed with a notch, and the closure having a head formed with an upwardly extending annular flange, and with a perforation extending through the lower surface of the head, and an upper surface of the head encircled by the flange, the movement of the closure serving to bring the perforation into alignment with the notch, a locking part located in the perforation and having a portion thereof projecting from the contiguous part of the head for entering the notch, a resilient disk arranged within the flange and coacting with the locking part for yieldingly forcing the same into its locking position, and a second disk arranged above the resilient disk and having its margin coacting with said flange, substantially as and for the purpose specified.

13. A grease cup comprising a base, a closure for the base connected thereto by screw threads, the base being formed with a notch, and a closure having a head formed with a

perforation extending through upper and lower surfaces of the head, the movement of the closure serving to bring the perforation into alinement with the notch, the head being also formed with an opening; a locking part located in the perforation and having a portion thereof projecting from the contiguous part of the head for entering the notch, a resilient disk mounted on the head and coacting with the locking part for yieldingly forcing the same into its locking position, the disk having an opening alined with said opening of the head, a follower movable toward and from the bottom of the base, means for operating the follower including a stem extending through said openings of the head and the disk, and means surrounding the stem and bearing against the disk for holding the same in position, substantially as and for the purpose described.

14. A grease cup comprising a base in the form of a receptacle, a closure for the base connected thereto by screw threads, the closure having a head overlapping the edge of the base, and the base being formed with a notch at said edge, the head being also formed with a perforation therethrough arranged to be brought into alinement with the notch as the closure approaches the limit of its movement toward the base, the head being also formed with a central opening, a resilient disk mounted on the head and arranged with its margin extending across the upper end of said perforation, the disk having a central opening alined with the opening of the head, a follower movable toward and from the bottom of the base, means for operating the follower including a stem extending through the central openings of the head and the disk, means surrounding the stem and bearing against the central portion of the disk for holding the disk in position, and a locking part in said perforation for coacting with the notch and the disk, substantially as and for the purpose set forth.

15. A grease cup comprising a base, a closure for the base connected thereto by screw threads, the base being formed with a notch, and the closure having a head formed with an upwardly extending annular flange, and with a perforation extending through a lower surface of the head, and an upper surface of the head encircled by the flange, the movement of the closure serving to bring the perforation into alinement with the notch, a locking part located in the perforation and having a portion thereof projecting from the contiguous part of the head for entering the notch, a resilient disk mounted on said upper surface of the head within the flange and coacting with the locking part for yieldingly forcing the same into its locking position, a second disk

above the first-mentioned disk and having its margin engaged with the upwardly extending annular flange, rigid means between the disks, a follower movable toward and from the bottom of the base, and a stem extending through the head and the disks and coacting with the follower, said stem being provided with means for preventing endwise movement thereof relatively to the head, substantially as and for the purpose set forth.

16. A grease cup comprising a base, a closure for the base connected thereto by screw threads, the closure having a head overlapping the edge of the base, and the base being formed with a notch in its edge opposed to the head, the head being formed with a perforation arranged to come into alinement with the notch as the closure approaches the limit of its movement toward the base, the head being also formed with a central opening, and an upwardly extending marginal annular flange forming a recess, the flange being formed with a seat, a resilient disk mounted on the head in the recess, the disk being arranged with its margin extending across the upper end of said perforation, and being formed with a central opening alined with the central opening of the head, a second disk of sheet metal having its margin resting on said seat, said second disk being formed with a central opening alined with the central openings in the first-mentioned disk and the head, a follower movable toward and from the bottom of the base, means for operating the follower including a stem extending upwardly through the central openings of the head and said disks, the stem having a thrust bearing for engaging the inner face of the head and a thrust bearing opposed to and spaced apart from the last-mentioned disk, a washer encircling the stem between the disks, and a washer encircling the stem between the second disk and the last-mentioned thrust bearing, substantially as and for the purpose described.

17. A grease cup comprising a base, a closure for the base including a head, a follower movable between the head and the bottom of the base, and being formed with a threaded opening, operating means including a threaded stem held from endwise movement relatively to the closure and extending through the threaded opening of the follower, and means interposed between the opposing surfaces of the closure and the follower for preventing turning of the follower with the stem, the part having one of said opposing surfaces being provided with a projecting shoulder for engaging the other opposing surface when the follower approaches the limit of its movement toward the head, substantially as and for the purpose specified.

18. A grease cup comprising a base, a closure for the base including a head, a follower movable between the bottom of the base and said head and being formed with
5 a threaded opening, means carried by the closure for operating the follower, said means including a threaded stem extending through the head and held from endwise movement relatively thereto, the stem ex-
10 tending through the threaded opening of the follower, and a conical spiral spring interposed between opposing surfaces of the head and the follower, and the part having one of the opposing surfaces being provided
15 with an annular shoulder arranged concentric with the spring and being of greater diameter than the largest diameter of the spring, said shoulder projecting toward the other opposing surface for engaging the
20 same and limiting the movement of the follower toward the head, substantially as and for the purpose set forth.
19. A grease cup comprising a base, a closure for the base including a head, a fol-
25 lower movable between the bottom of the base, and said head and being formed with a threaded opening, means carried by the closure for operating the follower, said means including a threaded stem extending through the head and held from endwise movement relatively thereto, the stem ex-
30 tending through the threaded opening of the follower, and a conical spiral spring interposed between the opposing surfaces of the head and the follower, the head being formed with an annular shoulder projecting toward the follower, said shoulder being of greater diameter than the largest diameter of the spring and arranged concentric with the spring, substantially as and for the purpose described.

In testimony whereof, I have hereunto signed my name in the presence of two attesting witnesses, at Auburn, in the county of Cayuga, in the State of New York, this 20th day of June 1911.
